UNITED STATES PATENT OFFICE

152,738

DESIGN FOR A VEHICLE WINDSHIELD VISOR

Howard C. Riemann, West Allis, Wis., assignor
to The Fulton Company, Milwaukee, Wis., a
corporation of Wisconsin

Application April 21, 1947, Serial No. 138,516

Term of patent 14 years

(Cl. D14—6)

To all whom it may concern:

Be it known that I, Howard C. Riemann, a citizen of the United States, residing at West Allis, in the county of Milwaukee and State of Wisconsin, have invented a new, original, and ornamental Design for Vehicle Windshield Visor, of which the following is a description, reference being had to the accompanying drawing, forming a part thereof.

In the drawing:

Fig. 1 is a front and side perspective view of a windshield visor embodying my new design; and

Fig. 2 is an enlarged rear and side perspective view thereof.

The dot-and-dash line showing in the drawing is for illustrative purposes only.

The characteristic features of my new design reside primarily in the end portions of the visor as best shown in Fig. 2.

I claim:

The ornamental design for a vehicle windshield visor, substantially as shown and described.

HOWARD C. RIEMANN.
